UNITED STATES PATENT OFFICE.

S. SICHEL AND S. FEUST. OF NEW YORK, N. Y.

IMPROVEMENT IN TICKET-REGISTER.

Specification forming part of Letters Patent No. 79,017, dated June 16, 1868.

To all whom it may concern.

Be it known that we, S. SICHEL and S. FEUST, of New York, in the county and State of New York, have invented a new and Improved Machine for Controlling the Receivers of Fares on Public Conveyances; and we do hereby declare that the following is a full, clear, and exact description thereof, which will enable others skilled in the art to make and use the same, reference being had to the accompanying drawings, forming part of this specification.

Figure 1 is a side view of the mechanism of our improved machine. Fig. 2 is a plan view of the same.

Similar letters of reference indicate corresponding parts.

The object of this invention is to prevent embezzlement on the part of those persons who receive fares on railroad-cars and other public conveyances where the use of our machine is applicable. It consists of the mechanism described in the following.

A is a base or pedestal, to which are affixed the uprights *ff*, which support two rollers, *J*, one above the other. These rollers are in contact with each other, their office being to withdraw the tickets or checks, which are in a continuous roll and wound on a spool, *D*, revolving on the shaft *h*, which latter has its bearings in the uprights *E E'*, affixed to the base *A*, as shown. The diameters of the rollers are such that one complete revolution will withdraw and protrude one ticket beyond the edges of the plates *g g*, which latter are affixed between the uprights *d d* and serve to guide the protruded ticket, and also as a sharp edge against which the ticket may be torn, to sever it from the remaining tickets of the roll. These plates converge toward their outer edges, so that only sufficient space is left between the said edges to permit the ticket to pass. The contact of the rollers is adjusted by means of the set-screws *e e*, which bear upon the reduced ends of the upper roller, the said reduced ends being in vertical slots in the uprights *f f*, whereby the rollers may be adjusted to the requisite pressure to withdraw and protrude any thickness of ticket-paper. The rollers are also provided with pinions *a a*, which engage with each other, and thus insure the rotation

of both rollers in a uniform manner. The rollers are turned by means of a crank-handle, *L*, of the cam *I*, which latter serves as a crank by being mounted on the end of the lower roller, as shown, and also as a cam-surface to raise the clapper *H*, pivoted on the upright *b*, and actuated downward by the spring *s*, attached to the under side of the clapper, as shown. The bell is for the purpose of calling the attention of the passenger about to receive the ticket, and by this means announces to him and others near that the conductor or person receiving fares and issuing tickets or checks therefor has drawn the ticket from the case in the proper manner, and not substituted a spurious ticket for the purpose of embezzling the amount of the fare. The knowledge of the fact that the absence of the sound of the bell will be a suspicious circumstance, which may be communicated to the proper authorities of the road or conveyance by any one of the passengers, will tend to prevent the receiver of fares from giving counterfeit checks, and thus act as a check upon him in this particular. The produced end of the lower roller bears a pinion, *q*, which engages with a cogged wheel, *K*, on the shaft *l*, as shown, the said shaft revolving in bearings in the upright *n* and the register-dial *m*, which latter also furnishes a bearing, it being affixed to the base *A*, as shown. A pointer, *r*, projecting from the shaft *l*, or its equivalent, indicates on the graduated face of the dial *m* the number of times the rollers have been revolved, and consequently the number of tickets that have been withdrawn from the spool *D*.

In practice, several of such dials and pointers will be arranged by a train of wheel-work to indicate units, tens, and hundreds.

In practice, the box will be carried at the waist by means of a belt or other suitable means, and being in a locked case the mechanism cannot be tampered with by the wearer for the purpose of defrauding his employers. A circular hole, *M*, in the side of the case allows the handle *L*, projecting through it, to be turned. The bell *G* is affixed to the upright *E'*, as shown.

The register-dials in practice will be protected by a glass plate set on or against the case *B* in any suitable manner.

We claim as new and desire to secure by Letters Patent—

The combination of the rollers J, plates g, can I, crank L, spool D, bell G, hammer H, with any suitable train of wheel-work connecting the rollers with the dials of any suitable registering apparatus, all substantially as shown and described, and for the purpose set forth.

The above specification of our invention signed by us this 18th day of February, 1868.

S. SICHEL.
S. FEUST.
